UNITED STATES PATENT OFFICE.

WILLIAM JAMES THOMPSON, OF WEST KOGARAH, NEW SOUTH WALES.

DRIVING MECHANISM.

SPECIFICATION forming part of Letters Patent No. 643,564, dated February 13, 1900.

Application filed December 8, 1898. Serial No. 698,675. (No model.)

To all whom it may concern:

Be it known that I, WILLIAM JAMES THOMPSON, civil engineer, a subject of the Queen of Great Britain, residing at Warialda street, 5 West Kogarah, near Sydney, in the British Colony of New South Wales, have invented new and useful Improvements in the Driving Mechanism of Pedal-Driven Machines, Specially Applicable to Bicycles and the Like, of 10 which the following is a specification.

The invention relates to certain improvements in the driving mechanism of pedal-driven machines, specially applicable to bicycles and the like, whereby on bicycles the 15 hanger-bracket and the intermediate driving-spindle are dispensed with, there being substituted therefor pedal-levers (with approximately reciprocating motion) connected to cranks revolving the axle of the driving-wheel, 20 and having varying fulcras adjacent to and relatively behind said axle, from which axle multiplying-gear imparts revolution to said wheel.

In order that this invention may be clearly understood, reference will now be made to the drawings herewith, in which—

Figure 1 is a side elevation of a bicycle, akin to what is known as a "safety-bicycle," constructed according to the present improvements. Figs. 2 and 3 are side elevation and plan, partially in section, on a larger scale, respectively, of the driving mechanism of said bicycle. Fig. 4 is a similar view to Fig. 3 of a modified construction of said driving mechanism. Fig. 5 is an elevation of toothed gear-wheels; and Figs. 6, 7, and 8, are plan and sections, respectively, of a pneumatic pedal.

The bicycle-frame is preferably an adaptation of the diamond frame, having front fork 40 *a* over the front wheel *A*, a backbone *b*, a diagonal or saddle pillar *c*, two back forks *d* and *e* over the back wheel *B*, and a cross-piece or bearer *f*, the back end of which forms a bottom fork or brace *f'*. With the exception 45 of the frame and the pedal-driving mechanism hereinafter particularly described all the parts of the bicycle are of constructions well understood.

The axle *B'* of the driving-wheel *B* is carried in brackets or hangers *C*, affixed on bottom fork *f'*, and the bearings it has therein are roller-bearings *B*², the balls of which may

be adjusted or tightened in their race (or two half-cups) *C*³ by the set-screws *C*³ in the bottom cover or half-bracket *C'*, which is fastened by bolts *C*⁴ to the fixed bracket *C*. 55

*C*⁴ is an oil-passage, and *C*⁵ an oil-pipe from the hub oil-case.

The driving-wheel *B* revolves on roller-bearings *B*³ against fixed and movable cones 60 adjusted as well understood, the gear-side one being rendered dustproof and oil-retaining by a guard or flange *G*⁵ on the clamp or nut *L*⁴ and the other one by a cover *L*⁵.

The pedals *D*, preferably of the kind hereinafter particularly described, are on levers *D'*, which have roller-bearing joints *D*², as shown, to cranks *B*⁴ on ends of axle *B'*. Backwardly of this joint *D*² each lever carries rollers or fulcrum-wheels *E* and *F* on roller-bearings *D*³ and *D*⁴, respectively. Each fulcrum-wheel *E* is adapted at certain parts of the stroke of the lever *D'* to have bearing against fulcrum-guides *E'*, affixed to the bottom fork *f'*, the configuration of which guide or groove is 75 preferably as shown, though it may be of other curved shape. Each fulcrum-wheel *F* has bearing upwardly against straight fulcrum-guide *F'* under the bottom fork *f'*, though this guide may be of other form than straight. 80

F' is a guard for preventing the back end of lever *D'* from dropping. As the fulcrum-guides *E'* and *F'* act as the fulcrum in different parts of the stroke of the lever *D'*, their shapes or configurations are independent of one another, though in practical working it is desirable that they be so constructed (say as illustrated in the drawings) that the impact of the rollers or wheels *E* and *F* on their respective guides will take place smoothly and without 85 shock. The rollers or wheels, if necessary, may be covered with rubber or the like to destroy or diminish noise. In the drawings the pedal-lever *D'* nearest the observer is shown at its lowermost position, while the other lever is at the top of the stroke, the position of the cranks *B*⁴ being marked, respectively, as 90 1 and 3 on their circle of travel, (dotted lines.) As shown, the rollers *E* and *F* on the nearer side are at points *1*^e and *1*^f, respectively, and 95 those on the other side at points *3*^e and *3*^f. In dotted lines the positions of the levers and rollers are indicated when the cranks *B*⁴ are at points 2, 4, and 5, respectively, the posi-

100

tions of the centers of rollers E and F being marked as 2^e , 4^e , and 5^e and 2^f , 4^f , and 5^f , respectively, the full course of the centers of rollers or wheels E and F being shown by dotted lines.

It will be seen from Fig. 2 that the wheel or roller E leaves the guide E' when the pedal has passed through the greater part of the downstroke and again engages with said guide 10 E' at a very acute angle on the up or back stroke, thereby causing the impact to be unnoticeable and in a sufficient manner to just relieve the wheel F from the guide F' until it is again about to leave the guide E' on the 15 downstroke of the pedal, when wheel F again bears on guide F', thus giving great power through the top part of the upstroke (for back-pedaling) and the greater part of the downstroke, while roller F enables the foot 20 to be carried back through the remainder of the revolution, and so on. If desired, extending downwardly from the frame in front of the cranks B⁴ there may be guides for the 25 pedal-levers to work in. The pedals D are attached to the levers D' by means of clamp D³ and screw bolt and nut D⁴, so that they may be set in any required position along the levers. An additional or auxiliary pedal D⁶ may be attached to each lever, so as to enable 30 long or short leg strokes to be given, if desired. The pedals are hinged or jointed on pin D⁵, so as to have a slight oscillating motion to adapt them to the position of the foot. The pedals are set on acute-vibration springs 35 or, as hereinafter described, have pneumatic treads.

In the modification illustrated in Fig. 4 there is but one back fork d, and the bottom fork f' terminates just behind the brackets or 40 hangers C (constructed with roller-bearings for the axle B', as hereinbefore described.) Instead of being connected direct with the crank B⁴ the pedal-lever D' carries on its 45 roller-bearing joint D² a bell-crank D^X, one end of which is connected to said crank B⁴, while the other carries on roller-bearing D³ a roller or wheel E in guide E', while on the 50 roller-bearing joint D⁴ of said lever D' is roller or wheel F in guide F'. The guides E' and F' 55 may be of any approved configuration having in view the easy and smooth working of the levers D' on varying fulera, and they are made in one piece and clamped to the forks and cross-piece or bearer f. Similarly, as here- 60 inbefore described, each fulera wheel or roller E, as likewise its complement the fulera wheel or roller F, is adapted at certain parts of its travel to have bearing against its guide and at other parts to be relieved therefrom. In 65 the drawings the cranks and rollers and bell-crank are shown in full lines as when at the top and bottom of the stroke, the crank B⁴ being in positions 1 and 3 on its circle of travel, the rollers E and F being correspond- 70 ingly and respectively at 1^e and 3^e and 1^f and 3^f . Further positions, as when the cranks are at points 2 and 4, are also shown. The

rollers E and F are correspondingly at points 2^e and 4^e and 2^f and 4^f on their respective center lines of travel. The corresponding positions of the joint D² are marked 1^d, 2^d, 3^d, and 4^d, respectively.

Whether the gear shown in Fig. 2 or the modification thereof shown in Fig. 4 be used it will be seen that a full stroke of the two 70 levers D'—that is, one movement up and one movement down of each lever—will turn the axle B' in its bearings a complete revolution, and continuous strokes will cause it to revolve evenly at a comparatively good speed; 80 but to increase the "gear" of the bicycle the revolution of the axle B' is multiplied while it is being imparted to the driving-wheel B, and this is effected by tooth or chain or other 85 convenient gearing contained in a casing G, attached by clips G' to the frame of the bicycle. In this casing is a pin H, with double cones H', forming roller-bearings H² for the hub or boss of a double gear-wheel or a double chain-wheel. This pin H is held on the sides 90 of the casing G, having slots or openings to allow it to be moved either toward or from the axle B' and hub B^X for adjustment by means of sliding pieces H³ on bolt H⁴, having nuts H⁵.

The larger driver-wheel J has epicycloidal teeth, and it is riveted or bolted or screwed to flange B⁵ on the axle B'. This wheel drives the pin-wheel K', riveted, screwed, or bolted to the boss or revolving piece K on ball-bearings H² on the pin H. The toothed wheel K' is also fixed to said boss K, and it engages with a driven wheel L', secured to the hub B^X by a left-hand-screwed circular clamp or nut L⁴ and formed of rollers L between side 100 pieces or cheeks L² of center piece L³. The wheel K' is equal and similar to wheel L'. Also the wheels J and K² are equal and similar, having the depressions or seating of the teeth cut deeper than the radius of the roller-teeth 110 below the pitch circle and narrower than the diameter of the rollers toward the bottom or base of the teeth to provide for adjustment, (consequent upon wear,) which is achieved by bringing the wheels K' and K², with the pin 115 H, closer to the axle B' by means of the adjusting-screws H⁴. Through this gearing the motion of the cranks B⁴ and axle B' is communicated to the driving-wheel B of the machine by the wheels J and K', through the 120 wheels K² and L, but accelerated in the proportion to the diameters of wheels J and K² over the wheels K' and L'.

Instead of the toothed wheels and pin-wheels, as described, chain-gearing might be 125 used, in which case the double-coned pin H would be the same; but for the wheels J and L' and K' and K² sprocket-wheels would be substituted, short chains passing around each driver and driven and adapted to be adjusted 130 by screws H⁴, while the whole might or might not be inclosed in the dustproof casing G or may be attached by clips inside or outside of the bicycle-frame.

The pneumatic pedal D consists of a tread M, honeycombed or roughened on its ends, with side guards M' on top of a leather or rubber box or outer casing N. This outer casing 5 N, containing an inner rubber tube O, sits on a bottom plate P, with end flanges P' taking upwardly to the guards M', from which pins M² protrude through slots P². It will be seen that when the inner tube O is filled with air 10 under pressure (through ordinary ingress-valve N') the tread M will be supported by such air-pressure, and thus the foot be pneumatically supported and defended from jars or shocks.

15 Having now particularly described and ascertained the nature of my said invention and in what manner the same is to be performed, I declare that what I claim is—

1. The combination with a driving-axle having a crank, and a driving-wheel on the axle, of a plurality of fulcra-guides of different configuration, and a pedal-lever pivotally connected with the axle-crank and having a plurality of fulcra to bear, respectively, against 20 the fulcra-guides and each of said fulcra at certain parts of its travel leaving or passing from engagement with its guide and at other parts of its travel bearing against its guides, substantially as and for the purposes described.

2. The combination with a driving-axle having a crank, and a driving-wheel on the axle, of a plurality of fulcra-guides of different configuration arranged in operative relation 25 and one having an extremity terminating at the extremity of another, and a pedal-lever pivotally connected with the axle-crank and carrying a plurality of fulcra to bear, respectively, against the fulcra-guides and each of 30 said fulcra at certain parts of its travel leaving or passing from engagement with its guide,

and one of said fulcra at certain parts of its travel moving from one of the fulcra-guides onto another, substantially as and for the purposes described.

3. The combination with a driving-axle having a crank, a driving-wheel loose on the crank, and multiplying-gearing operated by the axle to turn the driving-wheel, of a plurality of fulcra-guides of different configuration arranged above the level of the crank-axle, and a pedal-lever pivotally connected with the axle-crank and having a plurality of fulcra in rear of the axle to bear, respectively, on the fulcra-guides and each of which at certain parts, of its travel leaves or passes from engagement with its guide and at other parts of its travel bears against its guide, substantially as and for the purposes described.

4. The combination with an axle having a crank, a driving-wheel loose on the axle, and gearing for driving the wheel from the axle, of fulcra-guides located in rear of the axle, one being curved and the other substantially rectilinear and having one extremity terminating at one extremity of the curved guide to form practically a continuation thereof, and a pedal-lever pivotally connected with the axle-crank and carrying a plurality of fulcra rollers or wheels to travel, respectively, 60 against the fulcra-guides and each leaving or passing from engagement with its guide at certain parts of its travel, one of said fulcra rollers or wheels arranged to move from the rectilinear to the said curved guide, substantially as and for the purposes described.

Dated this 26th day of October, 1898.

WILLIAM JAMES THOMPSON.
